UNITED STATES PATENT OFFICE.

JOHN SCHOLL, OF ELK GROVE, CALIFORNIA.

SELF-FEEDER FOR THRASHING-MACHINES.

SPECIFICATION forming part of Letters Patent No. 251,799, dated January 3, 1882.

Application filed July 20, 1881. (No model.)

To all whom it may concern:

Be it known that I, JOHN SCHOLL, a citizen of the United States, and residing at Elk Grove, in the county of Sacramento and State of California, have invented a certain new and useful 5 Self-Feeding Attachment for Thrashing-Machines, of which the following is a specification.

My invention relates to improvements in self-feeding attachments for thrashing-machines; and the object of my invention is to provide a machine so constructed that the grain in the straw, after being dropped upon the feeding-platform, will be fed in a regular and automatic 10 manner to the separator of a thrashing-machine. I attain this object by the mechanism illustrated in the accompanying drawings, in which—

Figure 1 is a longitudinal section through 20 a portion of a thrashing-machine embodying my improvements. Fig. 2 is a cross-sectional view of the same.

Similar letters of reference are used to designate like parts throughout the several views.

The grain in the straw, as it is dropped from 25 the fork, falls upon the grating A, which is firmly secured to the main frame of the thrasher. Underneath this grating there is a movable grating, B, the slats of which correspond to the 30 spaces in the stationary grating immediately above it. This grating is provided with upwardly-projecting teeth or rods U U. To the underside of this movable grating I attach journal-boxes C C, through which pass the cranks 35 D D', the outer ends of which are journaled in suitable boxes set in the main frame of a thrasher.

Upon the outer end of the crank D, I key 40 the two pulleys E E', and upon the end of the crank D', I also key a pulley, (not shown in the drawings,) which is connected to the pulley E' by an endless belt or band.

Beneath the movable rack is placed the grain-carrier or endless belt G, which receives all 45 kernels of grain that may be shaken out, and which fall through the gratings A B. At any convenient point along this grain-carrier I place the drum H, upon a shaft, I, upon one end of which is keyed the pulley J, connected by an 50 endless belt or band with the pulley E. The other end of the shaft is provided with the pul-

ley K, connected by a suitable belt with the pulley L upon the crank-shaft M. Between the side boards of the thrasher, and upon the said shaft M, I place the roller N, provided 55 with projecting teeth or spikes O, the office of which will be more fully explained hereinafter.

Upon the outside of the machine, and about on a line with the inner end of the grating or screen A, I attach the guide-pieces P P, which 60 are set slightly inclined toward the outer end of the machine. That portion of the guide-pieces which extends above the top edge of the thrasher is slotted, as is clearly shown in Fig. 1, said slots forming a bearing or guide, in 65 which rises and falls the cross-bar Q, provided with downwardly-projecting rods or teeth R R. To the outer ends of this cross-piece are firmly secured the connecting-rods S S, the lower 70 ends of which are pivoted upon the crank-shaft M, as is seen at Fig. 2.

The operation of my improved self-feeder is as follows, to wit: The proper belt-connection having been made and the machine put in motion, the grain in the straw is deposited by any 75 well-known means upon the feed-grating A; and as the cranks D and D' are revolved they carry with them the feeder or movable grating B and impart a rotary reciprocating or four-motion feeding movement to it, or, in other 80 words, the feeder is so moved as to rise toward the stationary grating, move forward horizontally, fall to its former level, and assume its original position again. This movement will cause the upwardly-projecting teeth 85 or rods secured upon the feeder to pass upward through the slots in the fixed grating, enter the mass of straw and grain upon the feed-grating A, and force it forward in an intermittent manner to the separator. 90

The amount of material which is fed to the separator is regulated and controlled by the action of the bar Q and downwardly-projecting teeth R, so that as the teeth U of the feeder B advance they will force the straw toward the 95 separator, and the said bar Q will rise in its guides and permit a certain quantity of straw to be forced over the end of the feed-grating. Direction is given to it by the roller N, the projecting teeth of which roller will assist in directing the grain to the throat leading to the separator. As the feeder is resuming its origi- 100

nal position preparatory to carrying forward another quantity of straw containing grain to the separator the cross-bar Q will descend in its guides and its teeth prevent any surplus straw or grain from passing to the separator.

Having thus described my invention, what I claim, and desire to secure by Letters Patent, is—

In a self-feeding attachment for thrashing-machines, the combination, with the fixed grating A and movable grating B, having journal-boxes C C and teeth U, the latter adapted to enter the spaces in the upper grating, of the

crank-shafts D D', pulleys E E', grain-carrier G, drum H, having a shaft, I, carrying pulleys J K, the roller N, provided with teeth O, cross-bar Q, having teeth R, and suitable connecting and operating mechanism, substantially as and for the purpose shown and described.

In testimony that I claim the foregoing I have hereunto set my hand and seal this 29th day of June, 1881.

JOHN SCHOLL. [L. S.]
